UNITED STATES PATENT OFFICE

2,086,485

REFRIGERATING APPARATUS

George F. Weiher, Dayton, Ohio, assignor to General Motors Corporation, Dayton, Ohio, a corporation of Delaware

Application March 17, 1936, Serial No. 69,359

2 Claims. (CL. 230—221)

This invention relates to compressors of refrigerating systems and particularly to a valve arrangement therefor.

An object of the present invention is to provide an improved compressor for a refrigerating system.

Another object of the present invention is to provide a valve arrangement on or within the piston of a compressor which will operate efficiently and quietly in order that the compressor in which the valve arrangement is incorporated may be used in refrigerating apparatus of the household type.

A further object of the present invention is to provide a valve arrangement in or on the piston of the compressor of a refrigerating system which will be of increased structural strength and long life.

In carrying out the foregoing objects it is a still further and more specific object of the invention to provide a piston for a compressor of a refrigerating system which has a part movable relative to another part thereof and forming a complementary part of certain of the peripheral walls of the piston and which movable part of the piston forms a valve for sealing a passage or passages extending through the piston.

Further objects and advantages of the present invention will be apparent from the following description, reference being had to the accompanying drawing, wherein a preferred form of the present invention is clearly shown.

In the drawing:

Fig. 1 is a sectional view of a compressor of a refrigerating system having the present invention embodied therein and showing the refrigerating system diagrammatically connected to the compressor;

Fig. 2 is an enlarged vertical sectional view of the piston of the compressor shown in Fig. 1 having my invention incorporated therein; and

Fig. 3 is an enlarged fragmentary vertical sectional view of a piston within a cylinder of the compressor shown in Fig. 1.

Referring to the drawing for illustrating the present invention, I have shown a refrigerating system of the type suitable for installation in small refrigerators of the household variety. This type of apparatus is usually installed in cabinets which are placed in localities where noise caused thereby will be objectionable. Apparatus of this type must be automatic in operation and such operation thereof must be carried out quietly. The apparatus or system may comprise a compressor, generally represented by

the reference character 10, discharging refrigerant under pressure through a conduit 11 to a condenser 12. The compressed refrigerant is cooled and liquefied in condenser 12 in any suitable or conventional manner and flows into a chamber 13 containing a float or otherwise operated valve which controls the flow of liquid refrigerant to the evaporator 14. Refrigerant vaporized in evaporator 14 is drawn through a conduit 15, by suction created by the compressor 10, back to the compressor preferably to the crankcase thereof. The evaporator 14 is adapted to be mounted within an insulated compartment of a refrigerator cabinet (not shown) from which heat is to be extracted. Means for controlling a motor 16 which operates the compressor 10, through suitable belt and pulley connections 17, in response to the temperature produced by the evaporator 14 may be provided. This means may comprise an expansible bellows 18 connected by a pipe 19 to a bulb 21, mounted in thermal association with the evaporator 14, and having a volatile fluid sealed therein for actuating, upon movement of the bellows 18, a switch 22 interposed in the power line leading to motor 16.

Operation of motor 16 drives the compressor shaft 23 through the connections 17. Rotation of compressor shaft 23 causes rotation of eccentrics 24 and 25 mounted thereon for operating the pitmans 26 and 27 respectively to cause the compressor pistons 28 to be reciprocated within the cylinders 29. The end of the shaft 23 which extends through a wall of the compressor crankcase may be sealed by any suitable or conventional sealing means generally indicated at 31. Outlet check valves 32, which may be of the type fully disclosed in the Patent No. 1,852,203 to Otto M. Summers on April 5, 1932, mounted within the compressor 10 upon a suitable plate 40 located above the cylinders 29 together with the refrigerant flow control means 13 divide the refrigerating system into a low pressure portion and a high pressure portion. The low pressure portion of the refrigerating system includes the evaporator 14, conduit 15 and the crankcase of compressor 10.

The valve arrangement in the present disclosure employed to intermittently open and close the passages extending through the pistons 28 and which passages establish communication between the crankcase of compressor 10 and the cylinders 29 will now be described. Referring to Figs. 2 and 3 it will be noted that the pistons 28 each have a head 35 provided thereon and which

head includes a tapered wall surface 36 and a straight side walled portion 37 formed thereon. A raised portion 38 extending continuously around the tapered wall surface 36 provides a seat for the valve arrangement. Any desired number of holes 39 may be cut or bored through the wall of head 35 of piston 28 preferably substantially at right angles to and within the boundary of the raised portion 38 extending 10 around the tapered surface 36. These holes 39 provide the passage through the piston 28 for the flow of fluid from the compressor crankcase to within the cylinder 29 above the piston and are adapted to be closed during the upward movement of the piston 28 to enable the piston to compress the fluid in the cylinder 29. A groove 41 is cut inwardly of the straight vertical wall surface or portion 37 of the head of piston 28 for the reception of a locking or securing means 15 to be presently described. In order to eliminate the usual spring pressed valve or valves and the like from the construction of the piston 28 I provide a collarlike rim member 42 which surrounds the head 35 of piston 28 and forms a complementary part of the piston and particularly 20 a complementary part of certain peripheral walls thereof. It will be noted that this collar member 42 includes a tapered wall portion 43 which registers with the raised surface 38 formed on the 25 tapered wall portion 36 provided on the piston head 35. Collar member 42 also includes a skirt portion 44 which surrounds and registers with the straight side wall portion 37 provided on the head 35 of piston 28. This complementary collarlike part of piston 28 may carry a conventional 30 piston ring indicated at 45 and adapted to bear against the wall of cylinder 29. The collarlike member 42 has a groove 46 cut in the inner surface of the skirt portion 44 thereof and it will 35 be noted that this groove 46 is wider than groove 41 provided in the piston head 35 for a purpose to be presently described. An expandable ring 48 similar in construction to a conventional piston ring is located in grooves 41 and 46 and this 40 ring forms the locking means for securing the complementary collarlike portion 42 of piston 28 to the head thereof. In assembling the member 42 upon the head 35 of piston 28 the ring 48 is compressed within groove 41 to permit the 45 inner wall surface of the skirt portion 44 of collar member 42 to slip down over the ring 48. The spring tension of ring 48 will cause expansion thereof into groove 46 when this groove is moved into horizontal alignment with groove 41. Ring 50 55 48 is of such thickness from its inner to its outer cylindrical surfaces as to cause same to lie partly within groove 41 and partly within groove 46 to lock the collar member 42 upon the piston 28. The skirt portion 44 of collar member 42 may 60 be provided with openings (not shown) adjacent the ring 48 for permitting access to the ring by a suitable tool in order to compress same should it at any time be necessary to remove the collar member 42 from piston 28. It will be seen from 65 the foregoing that the raised surface 38 of the tapered portion 36 of piston head 35 forms a seat for the tapered surface 43 provided on the collar member 42 and that the collar member 42 forms a means adapted to close the fluid passage, 70 openings 39, which permits communication of the compressor crankcase with the cylinders above the piston 28. Thus the collar member 42 serves as a valve for controlling the flow of fluid from one side to the other of the piston and this member 75 extends in the same horizontal plane with the

top surface of the piston 28 so as to form a flat continuous surface entirely across the interior of the cylinder 29 to insure that when the piston is in its uppermost position all fluid compressed within the cylinder will be discharged 5 therefrom. In accordance with the foregoing described construction it is obvious that the collar member 42 serves as a valve and also forms a complementary part of certain peripheral wall surfaces of the piston. 10

In the operation of compressor 10, by motor 16, the pistons are reciprocated and suction created in cylinders 29 by the initial downward movement of the piston therein causes the collar member of the piston, which forms the piston valve, to be elevated relative to the other part of the piston as shown in Fig. 3 of the drawing. This movement of collar member 42 relative to the lower part of piston 28 is permitted due to the difference in the width of the groove 46, 20 formed in the skirt portion 44 of collar 42, relative to the width of the groove 41 provided in piston 28. Further downward movement of piston 28 in cylinder 29 increases the suction created above the piston and refrigerant fluid or 25 any other fluid flows from the compressor crankcase through the piston 28 by passing through the port holes 39, now uncovered by the collar member portion 42 of the piston, into the cylinder above the piston. When the piston reaches its 30 lowermost point of reciprocation and begins its upstroke the collar member part 42 thereof moves toward the main body portion 28 of the piston and the tapered surface 43 of collar 42 abuts against the raised portion 38 of the tapered 35 surface 36 provided on the piston head 35 to close or seal the port holes 39. Refrigerant fluid drawn into cylinders 29 is trapped therein between the top of piston 28 and the outlet check valve 32. Further upward movement of piston 40 42 compresses the refrigerant fluid and forces same under pressure through the outlet opening at the top of cylinder 29, controlled by check valve 32, through conduit 11 and into condenser 12. 45

From the foregoing it will be apparent that I have provided an improved valve construction for compressors which is quiet in operation and capable of operating for a long period of time. By making the improved valve construction as a complementary part of the compressor piston 50 the valve is of increased structural strength and this valve does not impair or reduce the efficiency of the compressor since same forms a continuation of the top and side peripheral walls of the piston and therefore provides a construction which insures that substantially all fluid drawn into the cylinder above the piston will be compressed in and expelled from the cylinder. My improved valve construction eliminates a certain amount of trouble ordinarily encountered in the use of compressors employing thin disk valves or the like which are frequently cut beyond repair or are broken by engagement thereof with the seat under high pressure conditions. The improved construction also eliminates the use of a spring or springs for forcing the valve 55 into engagement upon its seat and this reduces parts to a minimum as well as eliminating trouble which is frequently caused by breaking of such springs. 60

While the form of embodiment of the invention as herein disclosed constitutes a preferred form, it is to be understood that other forms might be adopted, all coming within the scope of the claims which follow. 70

What is claimed is as follows:

1. In combination with a piston adapted to be reciprocated within a cylinder of a compressor and having a passage therethrough for conveying a fluid from one side of the piston into the cylinder on the opposite side thereof, said piston having a straight side wall surface and a closed top wall, the side wall surface of said piston being closely fitted within said cylinder for guiding same therein, said piston also having a wall surface disposed intermediate and at an angle to the top and side wall surfaces thereof and forming a head on said piston, the fluid passage through said piston being located in the head thereof and opening into said angled piston head wall surface, a member including an angled wall surface corresponding to and registering with the angled wall surface of said piston, said member being movably secured to the piston to control the flow of fluid through the fluid passage in said piston, and said member cooperating with said piston to form a complementary part of the peripheral side and top wall surfaces thereof.
2. In combination with a piston adapted to be reciprocated within a cylinder of a compressor and having a plurality of passages therethrough for conveying a fluid from one side of the piston into the cylinder on the opposite side thereof, 5 said piston having a straight side wall surface and a closed top wall, the side wall surface of said piston being closely fitted within said cylinder for guiding same therein, said piston also having a wall surface disposed intermediate and 10 at an angle to the top and side wall surfaces thereof and forming a head on said piston, the fluid passages through said piston being located at spaced apart points in the head thereof and opening into said angled piston head wall surface, a collar including an angled inner wall surface corresponding to and registering with the angled wall surface of said piston, said collar being movably secured to the piston to control the flow of fluid through the fluid passages in 15 20 said piston, and said collar cooperating with said piston to form a complementary part of the peripheral side and top wall surfaces thereof.

GEORGE F. WEIHER.
